United States Patent Office

Des. 185,105
Patented May 5, 1959

185,105

COIN TRAY

Seymor Ullman, New York, N.Y.

Application December 6, 1957, Serial No. 48,804

Term of patent 7 years

(Cl. D52—4)

Fig. 1

Figure 1 is a view in perspective of a coin tray showing my new design;

I claim:

The ornamental design for a coin tray, substantially as shown.
